UNITED STATES PATENT OFFICE

146,066

DESIGN FOR A COMBINATION CLOCK AND RADIO

James F. Barnes, Chicago, Ill., assignor to Barnes
& Reinecke, Chicago, Ill., a copartnership

Application February 11, 1946, Serial No. 126,432

Term of patent 7 years

(Cl. D56—4)

To all whom it may concern:

Be it known that I, James F. Barnes, a citizen of the United States of America, residing at Chicago, in the county of Cook and State of Illinois, have invented a new, original, and ornamental Design for a Combination Clock and Radio, of which the following is a specification, reference being had to the accompanying drawings, forming part thereof.

Fig. 1 is a front elevational view of a combination clock and radio showing my new design;

Fig. 2 is a side elevational view thereof; and
Fig. 3 is a top plan view.

I claim:

The ornamental design for a combination clock and radio, as shown.

JAMES F. BARNES.
